UNITED STATES PATENT OFFICE

HAROLD S. BELL, OF SUMMIT, NEW JERSEY

APPARATUS FOR BATCH DISTILLATION OF MINERAL OILS

Application filed January 20, 1927. Serial No. 162,230.

This invention relates to the batch distillation of oils and has for its object to increase the efficiency of batch distillation by conserving the heat required, limiting the investment necessary and expediting the time required to conduct a series of batch processes.

In the case of many processes, especially where a precise test of residuum for viscosity, or flash and fire, or both are required, it is generally conceded that batch distillation is necessary. While continuous distillation processes are widely used and preferred for the sake of economy in their utilization of heat and apparatus employed, batch distillation when necessary has heretofore been inefficient through requiring more frequent idleness of the apparatus and inability to conserve the surplus heat of the vapors by pre-heating the feed as is common in continuous distillation processes. This is because the feed is shut off while the batch is being heated. Under the present invention these disadvantages are overcome and batch distillation is made more economical.

According to this invention, a pair of vaporizing or separating tanks are arranged so that either of them can be connected to a heater, one being operated while the other is being filled. In this way the feed can be pre-heated from the vapors of the operating tank. When the residuum has reached the required test, the heater is disconnected and immediately attached to the other tank so that no interruption in the heater is necessary. The feed can be interrupted but is preferably left connected to one tank while the residuum is being drawn off from the other and made ready to be filled.

Referring to the drawing, the single figure is a diagrammatic plan view of the preferred apparatus employed.

Two separating tanks, 10 and 11, are connected by suitable piping 12 to either of the circulating pumps 13 or 14 for drawing off material from the bottom of either tank so that the batch material in either tank may be circulated by pipes 14^a through the tubular heater 15 and thence back by pipes 15^a into the top of the tanks. The tanks are provided

with vapor lines 16 and 17 leading to the customary dephlegmators or bubbling towers 18 and 19. Heat exchangers 20 and 21 are located in each vapor line between the tower and the pipe 22 or 23 leading to the condensers. 25 and 26 are the return pipes for reflux from the towers. The supply for the tanks 10 and 11 is pumped through a series of pipes or conduits. For example the supply for either tank is pumped through the pipe 27, thence through either or both heat exchangers to either tank, the connections of each heat exchanger being such that the feed may pass through that exchanger first and then through the other in order that the feed may encounter the hotter vapors last. For this purpose three-way valves 28, 29, 30 and 31 or other manifolding devices are arranged as indicated. In this way the feed may be either from pipe 27 through the pipe 32, heat exchanger 20, out pipe 34, thence through the pipe 36 into the heat exchanger 21 through pipe 33, out through pipe 35 and then through pipe 38 to either tank. Or instead of going in this direction the feed may pass from pipe 27, first through pipe 33, heat exchanger 21, out through pipe 35, thence through pipe 36 into heat exchanger 20, through pipe 32, and out through pipe 34, thence through pipes 37 and 38 into either tank. For drawing off residuum, pipe 39 is connected to the bottom of either tank and leads through cooler 40, pump 41 and thence through pipe 42 to the place of residuum storage or treatment. 43 and 44 are bleeders leading from heat exchangers 20 and 21, respectively.

In operation the heater 15 is connected to one separating tank, for example, tank 10 so that the feed may be supplied to the tank 11 at the top to supply the desired quantity substantially continuously during the time when tank 10 is connected with the heater 15. The vapors from the tank 10 pass off through the line 16 and if light fractions are present, through the tower 18, thence through the heat exchanger 20 and out the pipe 22 to the condenser. If no light fractions are present the tower may be by-passed, or with heavy oils may be eliminated and the vapors sent

through the heat exchanger direct from the separating tank through pipes 16^a and 16^b. The feed of material into tank 11 is being pre-heated by the vapors from tank 10 and so 5 may cause some of the lighter fractions contained therein to be passed off through the vapor line 17, tower 19 and heat exchanger 21 or connected directly to the heat exchanger 21 by by-passing the tower through pipes 17^a and 17^b. The feed through pipe 27 should 10 in this case first pass through the cooler of the two heat exchangers, namely 21 and thence through the heat exchanger 20 where it contacts with the hotter vapors. The supply pipe from the heat exchangers to the tank 15 is preferably of larger diameter than the feed pipe 27 so that ample room may be provided for any vaporized portions. When the residuum in tank 10 approaches the desired test, 20 valves shown in the circulating line are manipulated to disconnect separating tank 10 from the heater and immediately connect the heater to tank 11 so that no interruption in operation of the heater is necessary. Two 25 circulating pumps 13 and 14 are useful in order that one may be in reserve. As soon as the tank 10 is disconnected from the heater the residuum is drawn off through the cooler 40 and as soon as emptied the tank 10 is then ready to have the feed turned into it so that it may be slowly filling up while the other tank 11 is operating with the heater. If desired the feed may be interrupted when the 30 residuum is being drawn off from tank 10, but preferably the feed is kept up into separating tank 11 while connected with the heater and until the tank 10 has been emptied when it is disconnected from tank 11 and turned into tank 10. When the residuum in tank 11 35 approaches the desired test it is then cut off from the heater which is connected back to tank 10 again and the process repeated, the tanks being alternately used but the circulation through the heater being continuous.

40 It will appear to those skilled in the art that a wide variety of materials may be treated by the described process in the layout shown. For example, untopped crude may be supplied and the lighter fractions passed off while being supplied and before the tank is connected to the heater. If desired the feed may be of heavier gravity material. By way of illustration, if it be assumed that it is desired to reduce a thousand barrels of 45 Pennsylvania crude oil to cylinder stock in 24 hours, each tank should have a capacity of about 700 barrels, the cycle of operation being arranged to bring down one of these tanks to the desired test in about 16 hours.

50 55 Thus the rate of feed into the unheated tank would be about 42 barrels per hour. At the start of the run the crude oil entering the tank that is accumulating a batch, that is the unheated tank, would be about 250° F. and at the end of the run it would get up to

about 450° F. This gives an average temperature to the accumulating batch of about 350° F. at which temperature considerable vaporization takes place in lighter fractions. About 25 to 45% of the work may be done 70 by means of the heat exchangers, the exact percentage depending upon the character of the oils run through the apparatus. Conservation of heat energy, continuity of operation and feed, the saving of time, the lessening of investment cost and adaptability of the apparatus to use with a variety of materials 75 are among the important advantages of this invention. The feed may be pre-heated by gases from the heater 15 or in other ways 80 when it is not desired to utilize the heat in the vapors.

I claim:

1. In an apparatus for the batch distillation of oils, the combination with a pair of vaporizing tanks, of a heater, means for connecting said heater with either tank, means for supplying feed to either tank, a vapor line from each tank, heat exchangers in the vapor line of each tank, means for passing the feed successively through said heat exchangers, and means for passing the feed through either heat exchanger first. 85

2. In an apparatus for the batch distillation of oils, the combination with a pair of separating tanks, of a tubular heater, means for connecting said heater to either tank, a pump for circulating the material through the heater, means for drawing off residuum from each tank, means for leading off vapors 95 from each tank, a heat exchanger in the vapor line from each tank, means for feeding either tank, means for passing the feed through either or both heat exchangers and through either heat exchanger first and then through 100 the other.

3. In an apparatus for the batch distillation of oils, the combination with a pair of separating tanks, of a tubular heater, means for connecting the heater to either tank, 110 means for circulating the material through the heater, means for drawing off residuum from either tank, a vapor line for each tank, dephlegmators and condensers in the vapor line of each tank, a heat exchanger between 115 a dephlegmator and condenser in the vapor line of each tank, means for passing the feed to the unheated tank through the heat exchanger in the vapor line of the heated tank, and means for passing the vapors around the 120 dephlegmator in either vapor line.

Signed at New York, in the county of New York and State of New York, this 19th day of January, A. D. 1927.

HAROLD S. BELL.
